Continuation-in-part of abandoned design application Ser.
No. 271,992, July 14, 1972. This application May 6,
1974, Ser. No. 467,844

Term of patent 14 years

Int. Cl. D20—02

U.S. Cl. D6—188

FIG. 1 is an elevational and perspective view of a card stand showing my new design; and

FIG. 2 is a top plan view of same.

The characteristic feature of my design resides in the frosted effect on the edges and notches of the stand as shown.

This is a continuation-in-part of design application Ser. No. 271,992, filed July 14, 1972, now abandoned.

I claim:

The ornamental design for a card stand, substantially as shown and described.
